US00D895640S

(12) **United States Design Patent** (10) **Patent No.:** **US D895,640 S**
Van Gerbig et al. (45) **Date of Patent:** **** Sep. 8, 2020**

(54) **DISPLAY SCREEN OR PORTION THEREOF WITH GRAPHICAL USER INTERFACE**

(71) Applicant: **Illumina, Inc.**, San Diego, CA (US)

(72) Inventors: **Eliza Van Gerbig**, Emeryville, CA (US); **Igor Freilafert**, San Diego, CA (US); **Jeffrey Pohlmann**, San Diego, CA (US)

(73) Assignee: **Illumina, Inc.**, San Diego, CA (US)

(**) Term: **15 Years**

(21) Appl. No.: **29/642,785**

(22) Filed: **Apr. 2, 2018**

(51) LOC (12) Cl. **14-04**

(52) U.S. Cl.

USPC **D14/485**

(58) **Field of Classification Search**

USPC D14/485-495

CPC G06F 3/048; G06F 3/0481

(57) **CLAIM**

We claim the ornamental design for a display screen or portion thereof with graphical user interface, as shown and described.

DESCRIPTION

FIG. 1 depicts a front view of a display screen or portion thereof with a graphical user interface showing a first embodiment of the claimed design.

FIG. 2 depicts a front view of a display screen or portion thereof with a graphical user interface showing a second embodiment of the claimed design.

FIG. 3 depicts a front view of a display screen or portion thereof with a graphical user interface showing a third embodiment of the claimed design; and,

FIG. 4 depicts a front view of a display screen or portion thereof with a graphical user interface showing a fourth embodiment of the claimed design.

The outermost broken lines illustrate a display screen and form no part of the claimed design. The remaining broken lines illustrate features of the graphical user interface that forms no part of the claimed design.

1 Claim, 4 Drawing Sheets
